United States Patent Office

Des. 180,495
Patented June 18, 1957

180,495

SMOKER'S STAND

Stanley Rysiewicz, Chicago, Ill.

Application October 24, 1955, Serial No. 38,541

Term of patent 7 years

(Cl. D85—2)

Fig. 1

Fig. 2

Fig. 3

Fig. 1 is a front elevational view of a smoker's stand, showing my new design.

Fig. 2 is a side elevational view thereof; and

Fig. 3 is a top plan view thereof.

I claim:

The ornamental design for a smoker's stand, as shown.
